UNITED STATES PATENT OFFICE.

WILLIAM HENRY BAIN, OF ST. LOUIS, MISSOURI.

SHOE WITH ANKLE-BRACE.

1,269,518.

Specification of Letters Patent. Patented June 11, 1918.

Application filed January 25, 1917. Serial No. 144,407.

To all whom it may concern:

Be it known that I, WILLIAM H. BAIN, a citizen of the United States, and a resident of the city of St. Louis and State of Missouri, have invented a new and useful Improvement in Shoes with Ankle-Braces, of which the following is a specification.

This invention relates particularly to the bottom construction of shoes, and its object 10 is to provide a resilient support for the arch of the foot which will correct any tendency of the arch to fall.

The invention consists in arranging a strap between the insole and outsole and lacing it over the ankle, the insole being loose from the outsole along the inside of the shank to permit it to rise from the outsole and conform to the natural curve of the instep. The invention further consists in an 20 insole and strap assembled as a separate article of manufacture, ready to be embodied in a shoe.

Further objects and details of the invention will appear in connection with the following description of the shoe illustrated in the accompanying drawings. The same reference characters designate the same parts in the several views.

Figure 1 is a side elevation of a finished 30 shoe, the insole and ankle brace being shown in dotted lines;

Fig. 2 is a bottom plan view of a partly completed shoe, following the welt sewing operation;

Fig. 3 is a cross-section of the partly completed shoe shown in Fig. 2, on the line 3—3 in said figure, looking in the direction of the arrows;

Fig. 4 is a top plan view of an insole and 40 ankle brace ready for embodying it in a shoe;

Fig. 5 is a side elevation of the insole and ankle brace shown in Fig. 4;

Fig. 6 is a bottom plan view of the same; 45 and

Fig. 7 is a cross-section of the insole and brace, on the line 7—7 in Fig. 6, looking in the direction of the arrows.

The shoe shown in the drawings comprises 50 an upper 11 which is inseamed to a welt 12, and an outsole 13 which is sewed to the welt in any suitable manner. The upper may have buttons or eyelets and lacing for securing the shoe on the foot. An ankle brace 55 consisting of a strap 14, having eyelets and a lacing 15 for drawing it tight, passes be-

tween the insole 16 and outsole 13 under the instep. The insole 16 is made in two parts, one of which is preferably leather and goes against the foot. The other part 17 of the 60 insole is canvas or other flexible material, and has an upstanding rib 18 of stiffened canvas secured around its edge for inseaming the welt and upper thereto. The insole and strap are loose from the upper and welt 65 along the inside of the shank; but are secured to the outer canvas part 17 of the insole by a line of stitches 19, and thereby are securely held in place. The brace may be stiffened by means of bone or metal stays 70 which are sewed into pockets in the portion which passes under the insole. The brace or strap 14 has a padded tongue 21 secured along one edge beneath the ends of the strap to protect the foot from the eyelets and 75 laces 15.

The shoe is made in the usual manner for welt shoes, using a special insole provided with a brace strap as shown in Figs. 4, 5 and 6. The leather top portion of the insole 16 is covered with a strip of canvas 17 on its under side, which in turn has a rib 18 around the edge of the canvas for inseaming. This rib may be formed in any suitable way. The canvas bottom 17 of the insole is 80 sewed to the insole by a line of stitches 19 around its outer edge excepting around the heel and along the inside of the shank. (See Fig. 6.)

The effect of the foregoing arrangement 85 is that when the foot is raised the strap pulls the insole away from the outsole on the inside of the shank to support the instep.

The invention is not restricted to the details of construction shown and described. 90

I claim the following as my invention:

1. A shoe comprising an upper, an insole and an outsole, said upper being secured to the outsole and loose from the insole on the inside of the shank, and a brace adapted to 100 encircle the instep and having a portion extending between the insole and outsole and secured to the outside shank portion of the insole.

2. A shoe comprising an upper, an insole and an outsole, a welt for securing said upper to the outsole, said welt being loose from the insole on the inside of the shank, and a brace adapted to encircle the instep and having a portion extending between the 105 insole and outsole and secured to the outside shank portion of the insole.

3. A shoe comprising an upper, an insole and a two-part outsole, a welt for securing said upper to the outsole, said welt being loose from the main part of the insole on the inside of the shank, and the second part of the insole constituting means for securing said welt to said insole said second part being secured to said main part around the forepart and on the outside of the shank.
- 10 4. An insole for a welt shoe, said insole comprising an inner part and an outer part secured together around the forepart and on the outside of the shank, and loose on the inside of the shank, and a channel, lip or rib on said outer part for inseaming.
- 15 5. A combined instep brace and insole comprising an inner part and an outer part secured together around the forepart and on the outside of the shank, and loose on the inside of the shank, and a brace member adapted to embrace the instep arranged between said inner and outer parts and secured thereto away from the inside of the shank.
- 20 6. A welt shoe comprising an insole having a bottom piece provided with an inseaming channel, lip or rib, said bottom piece being secured to said insole around the forepart and away from the inner edge of the shank, but loose from the insole at the inner edge of the shank.
- 25 7. A welt shoe comprising a stiff insole, and a flexible bottom piece provided with an inseaming channel, lip or rib, said bottom piece being secured to said insole around the forepart and away from the inner edge of the shank, but loose from the insole at the inner edge of the shank.
8. A shoe comprising an upper, an insole having its shank formed in two layers, and an outsole, said upper being secured to the outer layer and loose from the inner layer of the insole on the inside of the shank, and an instep brace arranged within the upper and having a portion extending between said layers of the insole.
9. An instep brace for shoes having inner and outer soles, the middle of said instep brace being adapted to extend between said soles and its ends having means for fastening it over the instep, and a pad or tongue attached to one end of said instep brace and adapted to lap under the other end of said instep brace to protect the top of the instep.

Signed at St. Louis, Missouri, this 22nd day of January, 1917.

WILLIAM HENRY BAIN.
